UNITED STATES PATENT OFFICE.

HOWARD C. CARMICHAEL, OF INDIANAPOLIS, INDIANA.

ELECTRICAL-SWITCH-CONTROLLING APPARATUS.

Application filed September 22, 1922. Serial No. 589,810.

To all whom it may concern:

Be it known that I, HOWARD C. CARMICHAEL, a citizen of the United States, residing at Indianapolis, in the county of Marion and State of Indiana, have invented a new and useful Electrical-Switch-Controlling Apparatus, of which the following is a specification, reference being had to the accompanying drawings, and to the letters and figures of reference marked thereon.

This invention relates to apparatus for controlling electrical-switches by means of railway car wheels, especially switches for making or breaking electrical circuits of signals or other devices, the invention having reference more particularly to an electrical-switch controlling apparatus that is adapted to be used in connection with a railway crossing gate and signal, such as that disclosed in my application for Letters Patent filed September 10, 1921, Serial No. 499,793, which has matured into Patent No. 1,475,682, Nov. 27, 1923, in which patent the principal features of the present invention are described.

An object of the invention is to provide an electrical-switch controlling apparatus of the above-mentioned character which shall be so constructed as to be practical and physically able to perform the function required of it, and under the severe conditions which must be imposed upon such apparatus when associated with the operation of railway trains.

Another object is to provide improved apparatus of the above-mentioned character which shall be composed of simple elements and not liable to become deranged or damaged in usual operations, which shall not be costly to manufacture or expensive to maintain, and which shall be durable and economical in use.

With the above mentioned and other objects in view, the invention consists in the novel arrangement of an electrical-switch, and an improved apparatus for operation and control thereof by means of car wheels moving on a railway track; and, the invention consists also further in the novel parts and in the combination and arrangement of parts as hereinafter particularly described and further set forth in the claims appended hereto.

Referring to the drawings,—Figure 1 is a fragmentary longitudinal section showing a portion of a railway track with which the

invention is associated, taken as on the line I—I on Fig. 2; Fig. 2 is a fragmentary top plan of a portion of the railway track and invention associated therewith, a portion 60 of the cover of the apparatus housing being broken away; Fig. 3 is a fragmentary section approximately on the line III—III on Fig. 2; Fig. 4 is a horizontal central sectional view of an electrical-switch suitable 65 for operation and control by the improved controlling apparatus, on an enlarged scale; Fig. 5 is a fragmentary section approximately on the line V—V in Fig. 1 on an enlarged scale; Fig. 6 is a fragmentary section 70 approximately on the line VI—VI in Fig. 3 on an enlarged scale; Fig. 7 is a section on the line VII—VII in Fig. 4; Fig. 8 is a horizontal detail section on the line VIII—VIII in Fig. 9; Fig. 9 is a fragmentary section on the line IX—IX on Fig. 2 on an enlarged 75 scale; and, Fig. 10 is a fragmentary section approximately on the line X—X in Fig. 1.

In the various figures of the drawings similar reference characters indicate corresponding elements or features of construction herein referred to in detail.

In the drawings the numeral 1 indicates cross-ties of a railway track comprising rails 2, 3 indicating a flanged car wheel in its usual relation to a rail of the track.

The invention comprises a housing which has a bottom base plate 4 which in proper position is secured upon a number of the cross-ties with one edge thereof adjacent to the rail. The housing has a pit comprising a side wall 5 and a bottom 6, the wall being fixed to the base plate in which is a suitable opening permitting access to the pit. The housing has also another pit comprising a wall 7 and a bottom 8, the wall being fixed to the base plate 4 at a suitable opening therein permitting access to the pit. The pits are arranged between cross-ties and adjacent to the rail 2. The base plate 4 has a wall 9 on its top upon which a cover 10 is suitably secured.

A pivot block 11 is arranged on the inner side of the web of the rail 2 and has ears 12 and 13 thereon which are secured by means of bolts 14 and 14' to the web. A rocker or pivot head 15 is connected by means of a horizontal pivot 16 to the block 11, and the rocker head has a vertical pivot 17 provided with a nut 18. An improved operating bar is provided which has a base portion 19 that is connected to the pivot 17 and re-

tained by the nut 18, an inclined portion 20 extending from the base portion upwardly to the inner side of the ball of the rail 2, a horizontal portion 21 extending from the 5 inclined portion along the rail, and a relatively obtuse angle portion 22 that extends from the horizontal portions and gradually away from the ball of the rail. The operating bar extends above the two pits and 10 may be moved pivotally away from the rail and also downward, the housing being suitably recessed or set sufficiently low to permit such movements. The operating bar is yieldingly held against the ball of the rail, 15 preferably by means of a curved lever arm 23 having a base portion 24 that is connected by means of a pivot 25 to the base plate 4, the arm having a contact end portion 26 that bears against a lug-bar 27 fixed 20 to the angle portion 22 of the operating bar, so that while the lever arm swings slightly horizontally after the operating bar is moved away from the rail, the lug-bar slides against the contact portion 26 when 25 the operating bar moves downward. The lever arm 23 preferably is stopped against a block 28 fixed to the base plate 4 to permit ready removal of the operating bar when making repairs.

30 An electrical-switch or circuit connector and a dash-pot are structurally combined and comprises a cylinder 29 which is secured upon the bottom 8 of the larger pit, the cylinder having suitable heads 30 and 31. A 35 pair of laterally elastic contact fingers 32 and 33 are supported by an insulating ring 34 secured into the cylinder and have connection with circuit wires 35 and 36 which may be connected with any desired electrical apparatus requiring electrical current.

40 A piston rod 37 is slidably arranged in the head 30 and has a piston 38 secured thereto which is fitted in the cylinder 29. A contact device 39 is secured to the piston 45 rod and insulated therefrom, and so designed and arranged as to permit it to be moved sliding between the contact fingers 32 and 33 whereby to form an electrical circuit. The piston rod has an upward extending 50 arm 40 that extends through a yoke 41 which is secured to the operating bar, the bar being permitted to freely descend relatively to the arm. The piston has an aperture 42 therein that is provided with a suitable valve 43 which may be designed to permit slight leakage through the aperture. The head 30 preferably is provided with an aperture 44 provided with a valve 45 on its inner side, the valve preferably being 55 designed to permit slight leakage through the aperture, so that air in the cylinder between the head 30 and the piston 38 may slowly leak from the cylinder. The space in the cylinder beyond the piston has connection 60 with the atmosphere, being preferably 65 through an aperture 46 in the wall of the cylinder. The arrangement is such that the electrical circuit is closed when the operating bar is moved away from the rail 2, but this is not arbitrary, since the arrangement 70 of contacts may be such as to cause the circuit to be broken or disconnected with a like movement of the operating bar.

The lever arm 23 is yieldably forced toward the rail 2 by means of a coil spring 75 47 connected to the arm and also to an anchor 48 secured to the housing, the spring being strained under suitable tension and of such length as to not be liable to become broken.

80 In the other pit a cylinder 49 is secured upon the bottom 6 and has a bottom head 50 and a top head 51. A piston 52 is arranged in the cylinder and has a piston rod 53 connected thereto that extends through the top head and has a cross-bar 54 fixed to its top, a bearing plate 55 being beneath the cross-bar and seated upon a coil spring 56 that is seated upon the top head 51. The cross-bar 54 extends through a yoke 57 85 that is fixed to the angle portion 22 of the operating bar adjacent to the end thereof, the yoke having a horizontal slot 58 through which the cross-bar extends and permitting the lateral movement of the operating bar, the cross-bar being vertically guided between two guide bars 59 and 60 on the side wall of the pit. The piston has an aperture 61 90 therein provided with a valve 62, and preferably the lower portion of the cylinder wall has a vent aperture 63 therein, the arrangement permitting the piston to be quickly forced downward and insuring slow upward movement of the piston. The operating bar is stopped in its upward movement, being 95 forced up by the spring 56, with the top of the bar on a level with the top of the rail 2, by means of a guide 64 fixed to the operating bar and extending downward adjacent to the inner side of the rail and having a 100 stop finger 65 thereon that extends under and in contact with the rail.

105 In practical use a wheel on the rail 2 when moving, as from the left hand side toward the right hand side on the drawings, 110 brings the flange of the wheel into contact with the angled portion 22 of the operating bar and forces the bar away from the rail, the bar causing movement of the piston rod 37 which carries the connector device 39 into contact with the switch fingers 32 and 33, the electrical circuit being complete whether the contact device 39 is 115 moved more or less by the operating bar which may be moved more or less by different wheels. After the wheel passes beyond the horizontal portion 21 the spring 47 retracts the operating bar by means of the lever arm 23, the air trapped between the head 30 and the piston 38 causing slow return move- 120 125 130

ment, being desirable to delay the return of the operating bar to the rail until after other wheels have passed, in order to avoid wear and tear of the apparatus. It will be understood, however, that adjustments may be made to permit rapid leakage of air and quick return of the piston 38 in case it is desired to quickly return the operating bar to the rail to break the electrical circuit. Horizontal movement of the operating bar on its pivot carries the yoke 57 idly across the cross-bar 54. When the wheel on the track rail moves in the opposite direction, from right to left, the flange of the wheel comes into contact with the top of the inclined portion 20 and forces the operating bar downward, which causes compression of the spring 56, the piston 52 being permitted to freely descend, and is retarded in its upward movement by the air trapped above the piston, it being desired to hold down the operating bar until all the wheels have passed, in order to reduce the wear of the apparatus to the minimum.

25 Having thus described the invention, what is claimed as new is:—

1. Electrical-switch controlling apparatus including an operating bar pivotally supported at one end for lateral movement, a curved lever arm pivotally supported adjacent to and engaging the operating bar, and a spring engaging the lever arm and supported to yieldingly force the operating bar in the direction away from the pivotal support of the lever arm.

2. Electrical-switch controlling apparatus including a pivot block having a horizontal pivot thereon, a pivot head connected to the pivot and having a vertical pivot thereon, an operating bar having an inclined portion connected adjacent to the lower end thereof to the vertical pivot, the bar comprising a relatively angular portion having a yoke fixed thereto, and means co-operating with the yoke to pivotally move the operating bar.

3. Electrical-switch controlling apparatus including a pivot block having a horizontal pivot thereon, a pivot head connected to the pivot and having a vertical pivot thereon, an operating bar having a relatively angular portion connected adjacent to the lower end thereof to the vertical pivot, the bar comprising a relatively angular portion having a yoke fixed thereto, and means co-operating with the yoke to yieldingly restrain pivotal movement of the operating bar.

4. Electrical-switch controlling apparatus including an operating bar comprising a base portion, a normally inclined portion extending from the base portion, a normally horizontal portion extending from the inclined portion, and a relatively obtuse angle portion extending from the horizontal portion; a pivot head arranged upon the top of the base portion of the bar and pivotally con-

nected thereto, a pivot block arranged on the rear side of the pivot head and having pivotal connection therewith, and a plurality of bolts connected with the pivot block to secure it in place.

5. Electrical-switch controlling apparatus including an operating bar comprising a base portion, a normally inclined portion extending from the base portion, a normally horizontal portion extending from the inclined portion, and a relatively obtuse angle portion extending from the horizontal portion; a pivot head to which the base portion is pivotally connected for horizontal movement, a pivot block to which the pivot head is pivotally connected for rotary movement with a horizontal axis of rotation, a plurality of bolts connected to the pivot block to secure it to a vertical support, a curved lever arm having at one end a pivot for support, the opposite end of the arm being arranged against the angle portion of the operating bar adjacent to the end thereof, and a coil spring connected to the middle portion of the lever arm.

6. In electrical-switch controlling apparatus, the combination of a hollow cylinder, two elastic contact fingers supported in the cylinder insulated therefrom, two circuit wires connected with the fingers respectively and extending out through the cylinder insulated therefrom, a piston movable in the cylinder, a piston rod extending through the piston and secured thereto, the rod extending out through the cylinder to be operated and controlled, a contact device secured to the piston rod and movable between and from the contact fingers, the device being insulated from the piston rod, and an operating bar having connection with the piston rod.

7. In electrical-switch controlling apparatus, the combination with a railway track rail, of a pivot block fixedly secured directly to the rail, a pivot head pivoted to the pivot block, and an operating bar pivoted to the pivot head and extending gradually upwardly therefrom to the adjacent side of the upper portion of the rail and thence gradually away from the rail.

8. In electrical-switch controlling apparatus, the combination with a railway track rail, of an operating bar including an inclined portion having pivotal connection at its lower end with the rail permitting downward and lateral movements of the bar, the bar having a horizontal portion extending against the upper portion of the rail and also a relatively obtuse angled portion extending away from the rail, a guide bar fixed to the said horizontal portion and extending downward at the adjacent side of the lower portion of the rail and having a stop arm thereon extending slidably against the under side of the rail, a spring arranged

to operate on said horizontal portion to yieldingly hold the operating bar to the rail, and a spring arranged under said angled portion to yieldingly support the operating bar with the stop arm against the rail.

9. In electrical-switch controlling apparatus, the combination with a railway track rail, of a covered housing arranged adjacent to the rail and having two pits, a curved lever arm pivoted in the housing, a spring connected to the housing and to said arm to draw the arm towards the rail, an operating bar having pivotal connection directly with the rail permitting downward and lateral movements of the bar, the bar extending between the rail and the lever arm in engagement with the arm, means in one of said pits connected with the operating bar to retard movement of the bar towards the rail, and means in the remaining one of said pits connected with the operating bar to retard upward movement of the bar.

10. In electrical-switch controlling apparatus, the combination with a railway track rail, of an operating bar including an inclined portion having pivotal connection at its lower end directly with the rail permitting downward and lateral movements of the bar, the bar having a horizontal portion extending against the upper portion of the rail and also a relatively obtuse angled portion extending away from the rail, said angled portion of the operating bar being provided on its under side with a yoke having a horizontal slot, a cylinder vertically supported below said yoke and having a head on its top, a piston in the cylinder and

having a valve to permit passage of air upward through the piston, a rod secured to the piston and having a cross-bar thereon extending through said slot, a coil spring under compression between said head and said cross-bar, and a spring arranged to yieldingly hold the operating bar to the rail.

11. In electrical-switch controlling apparatus, the combination with a railway track rail, of an operating bar including an inclined portion having pivotal connection at its lower end directly with the rail permitting downward and lateral movements of the bar, the bar having a horizontal portion extending against the upper portion of the rail and also a relatively obtuse angled portion extending away from the rail, the operating bar being provided with a yoke, a cylinder horizontally supported and having a head on one end thereof, a piston movable in the cylinder and provided with a valve to permit flow of air through the piston towards said head, a piston rod secured to the piston and extending through said head and having a lug thereon connected with said yoke, a spring and connections cooperating with said horizontal portion to yieldingly hold the operating bar laterally to the rail, a spring and connection to yieldingly support said angled portion of the operating bar and oppose downward movement thereof, and an electrical-switch to close a circuit arranged in the cylinder and controlled by the piston rod.

In testimony whereof, I affix my signature on the 13th day of September, 1922.

HOWARD C. CARMICHAEL.
